IMPACT PLATE

Edgar B. Symons, Hollywood, Calif., assignor to
 Nordberg Manufacturing Company, Milwaukee,
 Wis., a corporation of Wisconsin

Application October 24, 1938, Serial No. 236,611

4 Claims. (CL 83—46)

My invention relates to an improvement in impact crushers and particularly to impact plates or members usable with impact crushers.

One purpose is the provision of plates which shall be reversible and which may, therefore, enjoy an extended period of wear before they have to be rejected.

Another purpose is the provision of reinforcing means whereby rupture of worn plates is prevented during use.

Other purposes will appear from time to time in the course of the specification and claims.

The present application is a continuation in part of my co-pending application Serial No. 185,278, filed January 17, 1938, now Patent No. 2,192,606 issued on Mar. 5, 1940, which in turn is a continuation in part of my application Serial No. 710,592, filed February 10, 1934, and issued as Patent No. 2,110,851 on March 8, 1938.

I illustrate my invention more or less diagrammatically in the accompanying drawings wherein:

Figure 1 is a vertical transverse section;

Figure 2 is a detail;

Figure 3 is a partial section on the line 3—3 of Figure 1;

Figure 4 illustrates an impact member;

Figure 5 is a section through a modified impact member;

Figure 6 is a perspective view of the impact member shown in Figure 5;

Figure 7 is a section through a further modified impact member;

Figure 8 is a perspective of the impact member shown in Figure 7;

Figure 9 is a view of a variant form; and

Figure 10 is a section on the line 10—10 of Figure 9.

Like parts are indicated by like characters throughout the specification and drawings.

Referring to the drawings, I generally indicate any suitable supporting structure or element which may for example be a concrete or masonry foundation. Mounted thereon I illustrate horizontally extended I-beams 2, of which there may be two, the lower flanges 3 of which rest upon the foundation 1 and the upper flanges 4 of which serve as supports for the impact crusher. Any suitable shaft 14 may be employed, mounted in any suitable bearings not herein shown, since the impact crusher is not of itself part of the present invention. Keyed to the shaft 14 by the key 15 is a hub or body portion indicated as 16, with an outer generally cylindri-

cal portion 17 connected thereto in any suitable manner.

Extending outwardly from the member 17 are a plurality of flanges 19 having faces 20 herein indicated as somewhat rearwardly inclined. End members 21 may be employed, the entire structure being secured together as by bolts 22 with nuts 23, the various parts being appropriately apertured to receive them. Each such ring 21, one being shown herein, has a plurality of apertures 24, each such aperture having an inclined wedge face 25.

Seated against the faces 20 of the end members 19 are impact members 26, which I have shown for example in Figures 3 and 4. Each such impact member has at each end an end flange 27. Preferably the impact member so formed is flat and of uniform thickness throughout, including the flanges 27. The parts are so proportioned that the parts 27 penetrate the 20 apertures 24. In order to lock the impact members in position I employ wedge members, as shown for example in Figure 2, each such member including a wedge portion 28 adapted to seat in the aperture and having a wedge face 29 opposed to the face 25 of the aperture.

It will be understood that as the rotor rotates centrifugal force will tend to move the wedge outwardly with the face 29 sliding against the face 25 of the ring 21. The result will be to force 30 the opposite side 30 of the wedge forcibly against the face of the adjacent flange 27 of the impact member. Additional means for holding the wedge elements in position are shown and include an outer portion 31 having an elongated 35 aperture 31a through which passes any suitable bolt or securing member 32 with its nut 33. Positioned within the space formed by the rings 21 are removable wear plates 34. If desired, each bolt 32 may pass through one of these plates 40 and may thereafter perform the unitary service of securing the plate 34 in position as well as cooperating with the portion 31 of the wedge 28. Additional bolts may also be employed, as shown at 35 in Figure 1, with any suitable securing 45 nuts 36.

Any suitable housing may be employed, the details of which do not form part of the present invention, but which may include a plurality of bottom discharge members 40 and 41. A generally vertical feed spout 43 is indicated in Figure 1, having one edge 44 terminating closely adjacent the path of movement of the impact members and conforming to or secured to the arcuate housing member 45 which also conforms closely 55

to the path of the impact members and may be hinged if desired as at 46 and bolted or otherwise secured in position. The opposite edge of the spout as at 47 is cut substantially out of the path of movement of the impact members, the two edges being connected by inclined side edges 48. It will be understood that the edge 44 is in the direction of approach of the impact members so that after the impact takes place ample space is left between the path of the impact members and the edge 47 for the escape of the impacted particles.

I may employ any suitable normally fixed impact members for receiving the centrifugally expelled particles. I illustrate for example a plurality of removable plates 49, 50 which may be mounted in any suitable manner, as for example on backing members 51 which may be bolted in position as by the bolts 52 with the nuts 53, at 20 each end thereof.

It will be realized that whereas I have described and shown a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

30 For example, I illustrate two variant types of impact members. Referring to the form of Figures 5 and 6, it includes a flat body portion 60, with end flanges 61 and a rear reinforcing flange 62 extending from end to end of the impact plate and alined to and coextensive with the end flanges 61. In order to make easy the machining or grinding or forming of the contact edges of the reinforcing ribs 62, I provide channels or grooves 63 extending along the juncture between the rib 62 and the members 60 and 61. When the form of Figures 5 and 6 is employed, the members 19 are modified by the provision of a recess 64 adapted to receive the rib 62. The apertures 24 of the end plates 21 are also appropriately enlarged to permit the extension therethrough of the ends of the rib 62.

Referring to the form of Figures 7 and 8, it is substantially identical with the form of Figure 4, except for the addition along the upper and lower edge of a rearwardly extending reinforcing rib 65. To make easy the machining of the contacting faces, I also provide channels 66 between the member 65 and the body portion 26. In employing the form of Figures 7 and 8, the member 19 is modified by being somewhat shortened or recessed at the top as at 67 and by the provision of a recess 68 at the bottom, whereby an abutment portion 69 is provided which penetrates between the ribs 65 and abuts 60 against the rear face of the member 26.

Referring to the form of Figures 9 and 10, I illustrate an impact member having a forward face portion 70 and a plurality of rear reinforcements or thickened portions 71 divided by channels 72, the portions 71 and the channels 72 extending diagonally in relation to the maximum extension or length of the member.

In addition to the reinforcing effect, the employment of a set of thickened portions separated by slots 72 is of value in preventing any tendency of the plate to be bulged by the continuous hammering on one face. Manganese is subject to flow or deformation under impact and a flat plate such as shown for example in Figure 4 may under some circumstances tend to

bulge out. The employment of the slots 72 on the rear face of the plate gives the metal a chance to expand between the inner edges of the slots and the impacted surface of the plate. The effect will be to widen out the slots as the impact surface expands.

If the slots are cast straight across the plate, they might weaken the plate and make it less resistant under centrifugal force, but this disadvantage is entirely prevented by inclining them in the diagonal position in which they are shown in Figure 9.

The use and operation of my invention are as follows:

In impact crushers of the type in which my 15 impact members are employed, the material to be reduced is gravitally dropped, preferably in an unconsolidated stream, down the spout 43. The rotor is rotated at sufficient speed in relation to the acceleration by gravity of the particles to give a crushing impact of adequate force. The impact members are readily applied and removed and the wedge securing means, including the wedge face 29, has the important result of causing the speed of rotation of the 20 rotor itself to tighten up the wedges in response to the centrifugal outward movement of the wedges 28 and the apertures 24. However, the wedges can easily be loosened by loosening the nuts 33, and the inner wear plates 34 can readily 30 be removed and replaced.

I find it advantageous to make the members 26 and also the modified forms of Figures 6 and 8 of such a shape as to permit their ready reversal, since there is an inevitable maximum of 35 wear in the upper portion of the impact member. After each impact member has become somewhat worn, it can readily be reversed, preferably before being worn down too far. The result is a substantial increase in economy of 40 the manganese steel of which such members are generally made. This steel is an expensive material and the metal cost of crushing is a substantial factor in crushing costs and thus in the efficiency of a crushing device.

In the form of Figure 4, if it is assumed that the plate is worn all the way through in the center or is worn very thin, there may be some risk of rupture. Thus, while the plate of Figure 4 constitutes a substantial advance over conventional 50 practice, I find it desirable under some circumstances to prolong the life of the plate and eliminate the risk of rupture by providing the rearward rib 62 of Figure 6 or the two rearward ribs 65 of Figure 8, in order to provide a connection 55 extending from end to end of the plate which will not be worn through even though the front wear portion is worn practically down. This permits a definitely longer life of a given plate and further limits the metal wastage.

In forming manganese parts, smoothing and machining is an expensive and difficult operation owing to the nature of the material. I find it desirable to provide a minimum surface to be formed or machined for fitting to the opposed parts of the rotor or of its extending members 19. Thus in the form of Figure 6 the upper and lower surfaces of the rib 62 are separated by a channel 63 from the rest of the plate and can readily be machined or smoothed. The same is true of the inner faces of the ribs 65 of the form of Figure 8.

I claim:

1. In a breaker plate for impact crushers, a generally flat plate member having opposite faces generally parallel with each other, and having at 75

each end thereof an outwardly projecting integral lug lying in the plane of the plate and intermediate the corners of the plate, said lug being of substantially the same thickness as the plate, the plate, except for said end lugs, constituting a rectangle, one face of said plate having outwardly extending therefrom a plurality of parallel integral rearwardly extending reinforcing ribs extending from edge to edge of the plate, one of said 10 ribs being located along each of the long edges of the plate.

2. In a breaker plate for impact crushers, a generally flat plate member having opposite faces generally parallel with each other, and having at each end thereof an outwardly projecting integral lug lying in the plane of the plate and intermediate the corners of the plate, said lug being of substantially the same thickness as the plate, the plate, except for said end lugs, constituting a 15 rectangle, one face of said plate having outwardly extending therefrom an integral rearwardly extending reinforcing rib extending from end to end of the plate, intermediate the long edges thereof.

3. In a breaker plate for impact crushers, a 20 generally flat plate member having opposite faces

generally parallel with each other, and having at each end thereof an outwardly projecting integral lug lying in the plane of the plate and intermediate the corners of the plate, said lug being of substantially the same thickness as the plate, the 5 plate, except for said end lugs, constituting a rectangle, one face of said plate having outwardly extending therefrom an integral rearwardly extending reinforcing rib extending from end to end of the plate, intermediate the long 10 edges thereof, its ends extending rearwardly of and integral with said outwardly projecting lugs.

4. In a breaker plate for impact crushers, a generally flat plate member having opposite faces generally parallel with each other, said plate 15 constituting generally a rectangular, one face of said plate having outwardly extending therefrom a plurality of parallel integral rearwardly extending reinforcing ribs extending from end to end of the plate along opposite edges of the plate, and securing means for attaching said plate, spaced away from said reinforcing ribs and substantially 20 equidistant therefrom.

EDGAR B. SYMONS. 25
